UNITED STATES PATENT OFFICE.

WILLIAM A. ESTES, OF VASSALBOROUGH, ASSIGNOR OF THREE-EIGHTHS TO
ANDREW WEBBER AND HARTWELL B. HASKELL, OF CHINA, MAINE.

PLOW.

SPECIFICATION forming part of Letters Patent No. 252,291, dated January 10, 1882.

Application filed October 13, 1881. (No model.)

To all whom it may concern:

Be it known that I, WILLIAM A. ESTES, a citizen of the United States, residing at Vassalborough, in the county of Kennebec and State 5 of Maine, have invented certain new and useful Improvements in Plows, of which the following is a specification, reference being had therein to the accompanying drawings.

This invention relates to improvements in 10 that class of plows in which vertical friction-rollers are attached to the mold-board and landside, and horizontal rollers arranged to support the rear end of the plow and serve to crush the clods while assisting the draft. 15 The object of the invention is to provide improved means of journaling the rollers employed in the situations above referred to; and the invention consists in the construction of such rollers and in the manner of journaling and 20 arranging the same in connection with the rest of the plow, as hereinafter more fully described and claimed.

In the annexed drawings, which fully illustrate my invention, Figure 1 is a side view of 25 my improved plow, showing the outer side of the mold-board. Fig. 2 is a top view. Fig. 3 is a vertical longitudinal section. Fig. 4 is a rear view. Fig. 5 shows sectional detail views of the vertical anti friction rollers attached to 30 the mold-board and landside, and Fig. 6 shows a sectional view of the horizontal and adjustable land-rollers.

Like letters indicate like parts in the several views. 35 Heretofore the rollers sometimes employed in the construction of plows have been formed and arranged in such a manner that the wear necessarily comes directly upon the journals and bearings, so that in a short time their efficiency is seriously impaired. The journal-boxes or recesses for the reception of the journals of these rollers have also been liable to receive and retain dirt, thus adding greatly to the ordinary friction and obstructing the 40 free movement of the rollers as well as contributing largely to the wear of the parts in frictional contact. These difficulties are obviated by my improvements, in which I provide means for relieving the journals of the 45 effects of frictional wear by inclosing the same

in movable nipples so arranged as to exclude dirt, and at the same time receive and take up wear, such nipples being readily replaced, when required, at but a slight expense.

In the drawings, A represents the plow-beam, B the mold-board, and C the landside, these parts being constructed, arranged, and connected in any convenient and suitable manner.

The rollers *a* are preferably hollow, but 60 may be made solid, if desired. They are provided at each end with heads, on one of which is cast or otherwise attached a journal or arbor, *b*. As these rollers are arranged in the mold-board and landside in a vertical, or nearly 65 vertical, position, the end carrying the journal *b* is preferably placed uppermost. In the lower end of the roller is formed a recess, cavity, or journal-box, *c*, which may receive a journal or pivot, *d*, attached to a bearing, *e*, formed in 70 the lower part of the mold-board or landside.

It will be seen that the journal-box or cavity *c* formed in the lower end of the roller, as well as the journal-box *c* formed in the bearing *f* in the upper part of the mold-board and 75 landside, both open downward, so that whatever dirt comes in contact with the journals of the rollers will be caused to drop downward, and thus prevented from entering the boxes 80 to obstruct the movements of the upper journal within its box or of the lower box upon its journal or pivot.

In order to relieve the journals of the rollers, as well as the bearings, from the direct frictional wear, I inclose said journals in movable 85 nipples adapted to receive unavoidable strain, and capable of being readily removed and replaced, when required. The journals of the vertical rollers are provided with nipples *g*, which fit loosely within the journal-boxes *c* and inclose the journals *b* *d*, so as to protect the same on their sides and ends. These nipples also protect the bearings or interior of the boxes *c* *c* from the effects of the severe strain and wear that would result if the journals or pivots *b* *d* 95 were journaled directly in said boxes. The strain is thus greatly diminished and is expended chiefly upon the movable nipples, which, when worn, may be replaced at but little cost.

The rollers *a* are journaled in the manner 100

above described in the bearings *e f*, preferably formed in or attached to the back of the mold-board and landside at their upper and lower parts. These rollers are also arranged so as to 5 project partially through slots *h h*, formed in said mold-board and landside, and are each placed at the rear side of its slot, so that as the plow is moved forward the rollers in revolving backward will come slightly in contact with the 10 rear side of their respective slots, thus causing the dirt to be scraped from the rollers on the outside. By this simple means they are always kept clean and prevented from becoming clogged by contact with the soil.

15 An adjustable roller, *a'*, constructed and journaled in the same manner as the rollers *a a*, is arranged in bearings *i i'* at the rear end of the mold board, to which the lower bearing, *i*, is attached. The upper bearing, *i'*, of the roller *a'* 20 is attached to a bar or rod, *k*, that is adjustably supported in loops *m m*, secured near the lower ends of the plow-handles, or, if desired, to the upper rear parts of the mold-board and landside. The adjustable rod or bar *k* is secured by means of a thumb-screw, *p*, engaging with notches or openings formed in the bar, so that by loosening the screw the bar may be moved horizontally to the right or left, thus carrying with it the upper part of the roller *a'* 25 and retaining the latter either in a vertical or inclined position, according to the inclination of the land or of the furrow made by the plow.

At the rear end of the plow are arranged the horizontal land-rollers *D D*, which are loosely 30 journaled on loose collars, bands, or rings *t t*, through which passes a fixed shaft, *w*, that is secured in the lower ends of the downwardly-projecting arms *E E*, which are slotted at their upper ends and adjustably attached to the 35 handles or other parts of the plow by means of suitable bolts or screws passing through said slots. It will be observed that by this construction the rollers *D D* may be readily adjusted to any required height or inclination, and that 40 one of the supporting-arms *E* may be raised while the other is lowered, thus inclining the rollers according to the nature or incline of the land to be plowed. The movable bands or collars *t t* are placed on the fixed shaft *w* between 45 it and the horizontal rollers *D*, so as to take

up the wear that would otherwise come directly on the rollers and their shaft. By employing a fixed shaft for these rollers all wear at the lower ends of the arms *E E* is avoided. The shaft *w* is secured in place by suitable nuts at 55 either end, and a washer, *s*, may be placed on the shaft between the rollers for the purpose of holding the bands or collars *t t* in place.

The many advantages resulting from this manner of arranging and journaling the rollers employed in plows and similar cultivators have been but partially referred to above, but will be apparent upon observation. The efficiency of the rollers is largely increased at but a trifling cost, while, by reason of their greater durability and the prevention of wear in parts to which they are applied, a great saving is attained.

It is obvious that rollers and revolving shafts adapted for use in various situations may be 70 journaled in this manner with great advantage.

Having thus described my invention, what I claim as new, and desire to secure by Letters Patent, is—

1. An anti-friction roller for plows and other 75 cultivators, having the ends of its journal, shaft, or pivot loosely inclosed in a movable nipple, which is adapted to revolve in its bearing for the purpose of diminishing wear, all the parts being constructed and arranged substantially 80 as specified.

2. The combination, with the mold-board and landside of a plow having bearings *e f* and slots *h*, of the rollers *a*, arranged toward the rear sides 85 of said slots, and provided with recesses or journal-boxes *c*, and the movable nipples *g*, placed loosely within said journal-boxes and surrounding the journals of the rollers, substantially as and for the purpose set forth.

3. The combination, with a plow frame, of 90 the adjustable roller *a'*, having its journals inclosed in nipples *g*, and provided with a rod or bar, *k*, substantially as described.

In testimony whereof I affix my signature in presence of two witnesses.

WM. A. ESTES.
